UNITED STATES PATENT OFFICE.

AUGUST B. BECK, OF CRANFORD, NEW JERSEY, ASSIGNOR TO MEYER W. SCHLOSS, OF NEW YORK, N. Y.

GARTER-FASTENER.

1,094,112.

Specification of Letters Patent. Patented Apr. 21, 1914.

Application filed February 21, 1913. Serial No. 749,773.

To all whom it may concern:

Be it known that I, AUGUST B. BECK, a citizen of the United States, residing at Cranford, in the county of Union and State of New Jersey, have invented certain new and useful Improvements in Garter-Fasteners, of which the following is a full, clear, and exact description.

This invention relates to improvements in 10 garter fasteners.

One of the objects of the invention is to provide a form of fastener in which there will be no rigid corners to catch the hose when the garter is being adjusted nor exposed metal corners to contact with the flesh of the wearer if the fastener fails to lie flat against the leg.

Other objects of the invention will be evident from the specification and claims appended hereto, wherein,

Figure 1 is a perspective view showing the fastener and webbing to which it is attached; Fig. 2 is a similar view of the bottom portion of the fastener.

In the drawings 2 represents a head or button attached to the shank 3, both of which parts are of the usual form and over which the hose is adapted to be fastened in place by a key-hole shaped loop (not shown) which engages with the hose and holds it firmly against the shank. The shank 3 is riveted to the foot-plate 4 which extends to and is bent over the edge of the webbing. The ends of the plate 4 have connected to them at each end the supporting plates 5, 5, which are parallel to and directly beneath the foot-plate 4. The corners of the plates 5, 5, are cut away as at 6, the purpose of which will be later set out. These plates 40 form a sufficiently large supporting base to insure that the fastener will at all times lie flat against the leg of the wearer when the hose is attached thereto. The webbing is first laid on the foot-plate 4, then the supporting plates 5, 5, are bent over the same and are clenched against the webbing holding the fastener in place. The end 7 of the webbing is then folded back over the plates 5, 5, and sewed into place. This form of

fastener presents very little exposed metal as only a part corresponding to the thickness of the foot-plate 4 extends beyond the edge of the webbing, and this is remote from the end of the loop.

The plates 5, 5, are cut away, as at 6, to insure that there will be no sharp corners which, if the fastener fails for any reason to lie flat against the leg of the wearer, will tend to press into the flesh and make the garter extremely uncomfortable to wear. The corners of the plate 5 are cut away for this additional reason. In the preferred form, the corners of the plates being cut away, as at 6, the webbing will yield when an attempt is made to fasten the garter and the hose will be readily pulled over the fastener and secured to it.

Having described my invention, I claim:

1. In a garter fastener, the combination of a loop of webbing and a button carrying clip engaging the same, the clip comprising a loop transversely embracing one side of the web loop, that part of the clip lying between the sides of the web loop forming a foot plate and extending lengthwise of the web loop and being narrower at its extremities than the web whereby a foot plate for the button, of large area is provided without exposing parts thereof outside of the webbing.

2. In a garter fastener, the combination of a loop of webbing and a button carrying clip engaging the same, the clip comprising a narrow metal strap extending across the outer face of the web remote from the extremity of the web loop, and a wider metal foot plate extending transversely through the web loop and reaching to the bend or extremity of the web loop, said foot plate being narrower at its ends in the direction transverse to the web, than the web itself, for the purpose set forth.

In witness whereof, I subscribe my signature, in the presence of two witnesses.

AUGUST B. BECK
